UNITED STATES PATENT OFFICE.

KINSEY JONES, OF JANEVILLE, WISCONSIN.

SLEIGH-KNEE.

SPECIFICATION forming part of Letters Patent No. 645,262, dated March 13, 1900.

Application filed January 13, 1899. Serial No. 702,073. (No model.)

To all whom it may concern:

Be it known that I, KINSEY JONES, a citizen of the United States, residing at Janesville, in the county of Rock and State of Wisconsin, 5 have invented a new and useful Sleigh-Knee, of which the following is a specification.

The invention relates to improvements in sleigh-knees.

One object of the present invention is to 10 improve the construction of that class of sleigh-knees which are provided with grooves or ribs to receive rigid upright runner bolts or rods and which permit a limited oscillation of the runner, and a further object of 15 the invention is to enable such rods to be rigidly secured at their lower ends to the runner without perforating and weakening the latter.

The invention consists in the construction 20 and novel combination and arrangement of parts hereinafter fully described, illustrated in the accompanying drawings, and pointed out in the claims hereto appended.

In the drawings, Figure 1 is a perspective 25 view of a sleigh-knee constructed in accordance with this invention. Fig. 2 is a longitudinal sectional view. Fig. 3 is a transverse sectional view. Fig. 4 is a detail perspective view of the runner-plate. Fig. 5 is a similar 30 view of the knee detached.

Like numerals of reference designate corresponding parts in all the figures of the drawings.

1 designates a runner-plate provided at 35 opposite sides with longitudinal flanges 2, which are perforated for the reception of a transverse bolt 3, which secures the plate to a runner 4. The runner-plate is provided at its upper face with a concave seat 5, formed 40 in an enlargement and receiving the rounded bottom portion 6 of a knee 7, provided with a horizontal top portion 8, which is bolted to a beam 9^a. The ends of the enlargement in which the seat 5 is formed are provided with 45 vertical perforations 9 and form sockets or thimbles for vertical bolts or rods 10, which are connected at their upper ends with the rave 11. The concave seat is provided with a longitudinal rib or tongue 12, and the 50 rounded bottom portion of the knee is provided with a corresponding groove 13 to receive the rib or tongue, whereby the parts are

interlocked and supported against lateral strain.

The rods or bolts, which are vertical, have 55 their upper ends threaded, and their lower ends, which are provided with heads, are countersunk in the inner face of the runner-plate and are interposed between the same and the upper face of the runner. The upper threaded ends of the rods or bolts receive 60 nuts 15, which engage the rave, and when the latter is firmly bolted at its ends 16 to the runner the parts form a truss and provide a 65 firm construction.

The knee is provided at its front and rear faces with parallel vertical flanges 17, forming vertical ways or grooves for the rods or bolts and extending from the top to the bottom of the knee to afford a support on the 70 bolts or rods the entire length of the knee, whereby the latter is enabled to oscillate considerably without weakening the construction to permit the runner to yield to the configuration of the surface.

75 By separating the walls of the knee from each other, as shown in Figs. 2 and 3, a light hollow casting is formed which possesses the requisite amount of strength for supporting the load upon the sleigh, and by extending 80 the end walls above the tops of the side walls they embrace the beam of the sleigh, and thereby add to the strength of the structure.

The invention has the following advantages: 85 The device, which is simple and comparatively inexpensive in construction, is light, strong, and durable. The vertical flanges at opposite sides of the knee proper provide a continuous bearing for the rods, so that the knee may be permitted to oscillate considerably and still be supported by the rods or bolts; also, by providing the concave seat in the runner-plate bosses or thimbles are formed 90 for supporting and strengthening the lower ends of the rods or bolts, and the latter do 95 not have to be extended into the runner.

Changes in the form, proportion, and minor details of construction may be resorted to without departing from the spirit or sacrificing any of the advantages of this invention. 100

What is claimed is--

In a device of the class described, the combination with a runner, and a rave, of a runner-plate secured to the runner and provided

with sockets or thimbles terminating at the upper face of the runner and having their lower ends enlarged, the rigid upright rods having their lower ends arranged within the 5 thimbles or sockets of the runner-plate and provided with heads fitting in the enlarged portions thereof and abutting against the upper face of the runner, whereby they are rigidly connected with the latter without perforating the same, said rods being secured at 10 their upper ends to the rave, and a knee

mounted on the runner-plate and loosely arranged between the rods and provided with grooves for the reception of the same, substantially as described.

In testimony that I claim the foregoing as my own I have hereto affixed my signature in the presence of two witnesses.

KINSEY JONES.
